UNITED STATES PATENT OFFICE.

STARLEY F. BEASLEY, OF KANSAS CITY, KANSAS.

OUTLET VALVE FOR TANK CARS.

Application filed April 11, 1924. Serial No. 705,734.

To all whom it may concern:

Be it known that I, STARLEY F. BEASLEY, a citizen of the United States, and resident of Kansas City, county of Wyandotte, and State of Kansas, have invented certain new and useful Improvements in Outlet Valves for Tank Cars, of which the following is a specification, and which are illustrated in the accompanying drawings, forming a part thereof.

This invention relates to tank cars and has for its principal objects to provide an outlet valve that will not be influenced by distortion of the tank or by vibration, or by the wash of the lading during travel; that will not be impaired by damage to the outlet tube; that will have no movable parts below the bottom sheet of the tank, and that will permit the expansion of freezing liquids in the outlet tube.

Further objects and advantages of the invention will become apparent as the disclosure proceeds and the description is read in connection with the accompanying drawings, in which—

Fig. 1 is a fragmentary sectional view of a tank car equipped with a valve constructed and arranged according to this invention;

Fig. 2 is a side elevation of the valve;

Fig. 3 is a vertical section taken on the line 3—3 of Fig. 4;

Fig. 4 is a plan view of the valve and a fragment of the bottom sheet of the tank, and

Fig. 5 is a transverse sectional view taken on the line 5—5 of Fig. 3.

In the drawings 10 indicates a sill of the car frame carrying the tank 11 having a dome 12 at the top adjacent to the middle. Below the dome the bottom sheet 13 is provided with an opening that communicates with an outlet tube 14, having a flange 15, secured to the bottom sheet by rivets 16. The valve controlling the outlet includes a cage having a base ring 17, uprights 18 on the base ring connected at their upper ends by a top ring 19 and surmounted by a cap or cover 20 bolted to the top ring. The base ring inside of the uprights is equipped with a flat upwardly facing annular seat 21 which cooperates with the complementary portion at the bottom of a frusto-conical valve head 22. The cap 20 has a boss 23 threaded to receive a valve stem 24, loosely swiveled at 25 to the valve head. Between the valve head and the valve seat is an acid, oil and

fireproof gasket 26. The threaded stem 24 is loosely connected by a pin 34 with a forked operating rod 35 extending upwardly through a guide 46 in the dome and equipped with a hand wheel 27 at its upper end.

The opening in the bottom sheet is larger than the bore of the outlet tube 14 and extends back over the flange 15, as indicated at 28. The base ring 17 extends within the opening in the bottom sheet and is welded thereto, as indicated at 29. The base ring 17, the uprights 18 and the top ring 19 are readily formed as a single casting, the uprights being composed of webs 36 and tapered flanges 37 connecting the base and top ring. The flanges 37 cooperate with the heads 38 of the bolts 39 to prevent rotation when the nuts 40 are being run down.

The valve may be easily opened and securely closed by turning the hand wheel 27 in the appropriate direction. When closed the screw 24 extending between the top of the cage and the valve acts as a rigid strut holding the valve head securely against the seat. The valve cage being relatively short and quite rigid is not affected by the distortion of the car, or the wash of the liquid, etc., that impair the action of the valves now in service.

Since no part of the valve projects below the bottom sheet into the outlet tube, damage to that tube whether causing a severance at the breaking groove 30 or entirely dislodging the outlet tube, does not affect the functioning of the valve.

The seating of the valve head is not disturbed by pressure from below, but expansion due to freezing of liquids in the outlet tube is accommodated by air trapped in the pocket of the valve head.

The valve seat does not have to be ground or resurfaced and since the valve head is merely forced against the gasket 26 without any rotary motion the gasket will endure a long period of service.

I claim as my invention:

1. In a tank car, the combination of a bottom sheet having an opening therein, an outlet tube below the bottom sheet and communicating with the opening, a valve cage carried by the bottom sheet above the outlet tube, an annular upwardly facing seat in the cage, a frusto-conical valve head having a pocket in its underside surrounded by an annular portion for cooperation with

said seat and a threaded stem connecting the valve head with the cage.

2. In a tank car, the combination of a bottom sheet having an outlet therein, an outlet tube secured to the bottom sheet, a valve cage including a base welded to the bottom sheet above the outlet tube, a valve seat within the cage adjacent to the bottom, a valve head and means acting between the cage and the head to hold the valve on the seat.

3. In a tank car, the combination of a bottom sheet having an opening therein, an outlet tube secured to the bottom sheet, a cage composed of a base ring and a top ring integrally connected together by uprights, the base ring being connected to the bottom sheet and having a valve seat on

its upper face, a frusto-conical valve head in the cage, a cover attached to the top ring, 20 and a valve stem having threaded engagement therewith and connected to the valve head.

4. In a tank car, the combination of a bottom sheet having an opening therein, an outlet tube secured to the bottom sheet, a cage composed of a base ring and a top ring integrally connected together by uprights, the base ring being welded to the bottom sheet above the outlet tube and having a valve seat on its upper face, a frusto-conical valve head in the cage, a cover attached to the top ring, and a valve stem having threaded engagement therewith and connected to the valve head. 30

STARLEY F. BEASLEY.
